UNITED STATES PATENT OFFICE

ARTHUR LOLLO, OF BROOKLYN, NEW YORK

DESIGN FOR A SHAKER TRAY

Application filed February 23, 1932. Serial No. 42,958. Term of patent 3½ years.

To all whom it may concern:

Be it known that I, ARTHUR LOLLO, a citizen of the United States, residing at Brooklyn, in the county of Kings and State of New York, have invented a new, original, and ornamental Design for a Shaker Tray, of which the following is a specification, reference being had to the accompanying drawings, forming part thereof.

In the drawings:—

Fig. 1 is a top plan view of the shaker tray, showing my new design; and

Fig. 2 is a side elevation of the same.

I claim:

The ornamental design for a shaker tray, as shown.

ARTHUR LOLLO.
